Patented Aug. 17, 1920.

FIG. 1

UNITED STATES PATENT OFFICE.

HERBERT H. MACOMBER, OF KENDALLVILLE, INDIANA, ASSIGNOR TO FLINT & WALLING M'F'G CO., OF KENDALLVILLE, INDIANA, A CORPORATION OF INDIANA.

PRESSURE-REGULATOR.

1,349,843.

Application filed March 2, 1917. Serial No. 151,921. ♦

Specification of Letters Patent. Patented Aug. 17, 1920.

To all whom it may concern:

Be it known that I, HERBERT H. MACOMBER, a citizen of the United States of America, residing at Kendallville, Noble county, Indiana, have invented new and useful Pressure-Regulators, of which the following is a specification.

This invention relates to mechanism for the automatic maintenance and control of pressure.

This invention has utility when incorporated in electric control and maintenance of fluid pressure in hydro-pneumatic installations.

15 Referring to the drawings:—

Figure 1 is a fragmentary view of an embodiment of the invention in an electric actuated hydro-pneumatic plant or installation adapted for household use;

20 Fig. 2 is a plan of the pressure regulator of Fig. 1; and

Fig. 3 is a section on the line III—III, Fig. 2.

The suction line 1 may extend to the 25 hydro-pneumatic pump 2 mounted on the platform 3 with the electric motor 4 connected thereto by the driving belt 5 for operating the pump to supply compressed air and water to the line 6 and the reservoir 7. The pressure connection from the pump 2 may have the waste valve 8 and the pressure relief valve 9.

The pressure connections from the pump as shown embody the line 10 to the automatic pressure regulator at which there is the threaded connection 11 to the chamber 12 by opening 13, one side of said chamber being formed by the flexible diaphragm 14. The opposite side of the diaphragm in this 35 chamber has coacting therewith the disk 15 provided with a plunger 16 extending through the opening 17 to engage the lever 18 of the third class, having the fulcrum 19 in the bracket 20. Extension 21 from the 40 chamber 12 has the bolt 22 surrounded by the compression spring 23, which may be adjusted by the nut 24 to vary its action upon the lever 18 to resist movement of the plunger 16, and thereby permit adjusting 45 the pressure at which the device is to act.

In hydro-pneumatic installations for household use, the spring 23 may be adjusted to have a range for being thrown by the plunger 16 when the pressure rises above

fifty pounds, and to throw the plunger 16 55 when the pressure falls below thirty pounds. These points of pressure may be varied to adapt it to the desired conditions.

Mounted on the bracket 25 of the housing for the chamber 12 is the fulcrum bearing 26 for the third-class lever 27 having the power acting thereon through pin 28 from the lever 18. The lever 27 extends to the link 29 connected by the link 30 to the third-class lever 31 having the fulcrum bearing 32 in the extension 33 from the regulator chamber 12. This third third-class lever 31 in the compound lever linkage series from the plunger 16 extends to a pair of switch elements 34 each embodying a heavy 70 outer spring leaf and intermediate lighter laminations as a terminal.

From the motor 4 extends line 35 to the terminal 36 closed by one of the members 34 to connect with the terminal 37 and supply line 38. This supply line circuit is completed through the line 39 to terminal 40 closed by the other terminal 34 to the terminal 41 and line 42 to the motor 4.

80 In the shifting of the lever linkage mechanism, there is a throwing of the switch or terminal elements 34 into and out of circuit closing relation by the passing of the link 30 by a dead point as to the fulcrum 32, due to the raising, or lowering of the link 29. This throwing action is effected by the link 29 which in reality is a lever having the extension 43 connected by the bolt 44 to the ear 45 on lever 27. This bolt 44 has adjusted thereon the compression spring 46 tending 90 to force the upper end of this lever 43, 29, away from the diaphragm chamber, and accordingly the lower end toward the diaphragm chamber, thus tending to shift the link 30, and with it the lever 31 95 out of dead point relation as the link 29 is moved past such dead point. Adjusting of this spring 46 varies the responsiveness of this dead point shifting, while adjusting of the spring 23 varies the pressure range control as to the diaphragm actuation. There may be some relative adjustments desirable between these two springs in reaching certain desired conditions for operation.

100 The throw limit of the lever 31 away from such closing position is limited by the rocking lever or dog 47 having the fulcrum bearing 48 in the bracket 49 rising from

the extension 33 from the chamber 12. This dog 47 has the ledge 50 upon which the free end of the lever 31 may rest when the switch is opened, this dropped or opened position of the dog 47 being determined by the remote end or arm 51,—this arm coacting with the cross web in the upper arm 43 of the lever 43, 29. In the shifting of the switch to closed position, this dog 47 has its end 51 forced downward and there is a supplementing of the action of link 30 lifting past the dead point in that the cam 52 of the dog 47 rides under the free end of the lever 31 and brings the switch into firm terminal contacting relation.

There is accordingly produced a device of positive throw, delicately responsive to conditions arising in domestic water power plants, especially when used in connection with the pump of United States Patent No. 1,174,172.

What is claimed and it is desired to secure by United States Letters Patent is:

1. A pressure regulator embodying a diaphragm, a switch to be actuated, and intermediate mechanism including a plunger, snap throw effecting linkage for the switch, connecting means between the plunger and linkage, and a dog movable independently of the linkage and actuatable from the connecting means to hold the switch closed.

2. A pressure regulator embodying a

pivoted switch arm, a first link connected to the arm and approximating the direction of the arm, a second link extending transversely of the arm and connected to the first link, a diaphragm, a plunger coacting with the diaphragm, a first lever actuatable by the plunger, a second lever connected to the first lever, and adjustable yieldable means mounted on the second lever and coacting with the second link for rocking the second link as to the second lever for shifting the switch arm.

3. A pressure regulator embodying a pivoted switch arm, a first link connected to the arm and approximating the direction of the arm, a second link extending transversely of the arm and connected to the first link, a diaphragm, a plunger coacting with the diaphragm, a first lever actuatable by the plunger, a second lever connected to the first lever and the second link, a spring coacting between the second lever and the second link for rocking the second link as to the second lever, said second link as actuated from the plunger effecting longitudinal movement of the second link, and a dog rockable independently of the links and coacting as throw limit control means for the switch arm.

In witness whereof I affix my signature.

HERBERT H. MACOMBER.
